DESIGN FOR A FINGER RING

Felix P. Kinsley, St. Louis, Mo.

Application August 24, 1934, Serial No. 53,052

Term of patent 7 years

To all whom it may concern:

Be it known that I, FELIX P. KINSLEY, a citizen of the United States, residing at the city of St. Louis, State of Missouri, have invented a new, original, and ornamental Design for a Finger Ring, of which the following is a specification, reference being had to the accompanying drawing, forming part thereof.

Fig. 1 is a perspective view of the finger ring, showing my new design.

Fig. 2 is an elevation showing one side of the finger ring, the opposite side having the same design features.

The lining for color indicates black.

I claim:

The ornamental design for a finger ring, as shown and described.

FELIX P. KINSLEY,
